UNITED STATES PATENT OFFICE.

CHARLES JOHN SCHERRER, OF COUNCIL BLUFFS, IOWA.

COMBINED HOIST AND CONVEYER.

1,143,786.

Specification of Letters Patent. Patented June 22, 1915.

Application filed November 19, 1914. Serial No. 873,043.

To all whom it may concern:

Be it known that I, CHARLES JOHN SCHERRER, a citizen of the United States, residing at Council Bluffs, in the county of 5 Pottawattamie and State of Iowa, have invented certain new and useful Improvements in Combined Hoists and Conveyers; and I do declare the following to be a full, 10 clear, and exact description of the invention such as will enable others skilled in the art to which it appertains to make and use the same.

My invention relates to improvements in combined hoisting and conveying devices 15 and has for its main object to provide an extremely simple device of this character which may be easily and inexpensively manufactured, and which may be advantageously used as either a conveyer or a 20 hoist, or as both.

In carrying out this object, a pair of inclined sections are hingedly connected at their upper ends and equipped with rollers at their lower ends, and a hoisting device 25 is supported from the structure thus formed.

A further object of the invention becomes to provide novel means whereby the two sections may be swung outwardly, thereby causing their upper ends to lower, and 30 whereby these sections may be again moved toward each other to cause their upper ends to rise, it being understood that the hoisting device has been properly attached to the goods to be raised.

With the above and minor objects in view, 35 the invention resides in certain novel features of construction and combination herein described and claimed, and shown in the drawings wherein;

Figure 1 is a side elevation of a device 40 constructed in accordance with my invention, showing the position thereof when an article is to be raised; Fig. 2 is a vertical longitudinal section showing the position of 45 the parts when such an article is raised; Fig. 3 is a side view showing another manner in which the device may be used for hoisting; and Fig. 4 is an end view.

In these drawings, forming a part of this 50 application, the invention is shown as comprising two sections 1 and 2 which are hingedly connected at their upper ends and equipped with rollers 3 at their lower ends. Each of the sections 1 and 2 comprises a 55 pair of parallel legs 4 which are connected at their bottoms by transverse bars 5, the

rollers 3 being mounted on the lower ends of the legs as shown.

Secured to the upper ends of the legs 4, 60 are hinge leaves 6 which are provided with interengaging knuckles 7 on their upper ends, the reduced ends of a ridge bar 8 being passed through said knuckles and provided with nuts 9 as shown. By this construction, an inverted V-shaped frame is 65 provided, the two halves of which are hingedly connected at their upper ends.

Depending from the center of the ridge bar 8 and preferably held thereon by a hook 10, is a sheave 11 over which a hoisting element 12 passes. This element is here shown in the form of a cable, but it will be understood that a chain or ordinary rope could well be employed. One end of the cable 12 depends centrally between the two sections 75 1 and 2 and carries a chain 13 on its lower end, the center of the chain being attached to the cable, while the ends of the chain are equipped with a pair of grappling hooks 14. The other end of the cable, however, de- 80 pends between the legs 4 of the section 1 and is wound around a transverse shaft 15 which constitutes a windlass having a crank 16 at one end, and a pawl and ratchet mechanism 17 whereby it is held against move- 85 ment in one direction until the pawl is released.

Secured at their lower ends to the trans- 90 verse bar 5 of the section 1, is a pair of adjusting cables 18 which rise from their connections with said bar and pass over guide pulleys 19 and 20, which are carried re- 95 spectively by the upper ends of the legs of the frames 1 and 2 respectively, said cables then depending from the pulleys 20 and be- 100 ing wound around a second windlass 21, which may be rotated by the crank 16 which is detachable, the windlass 21 being also provided with a pawl and ratchet mechanism 22 for preventing its rotation in one direction.

With the parts constructed as above de- 105 scribed, the chain 13 and the grappling hooks 14 normally stand adjacent the sheave 11, and the cables 20 are loosened by rota- 110 tion of the windlass 21 to allow the two frames 1 and 2 to move outwardly as seen in Fig. 1, whereby the ridge bar 8 is lowered, thereby allowing the hooks to be engaged with a barrel B or other device to be raised. The windlass 21 is now rotated in the proper direction to wind the cables 18, thereby pull-

ing the two sections 1 and 2 together to gradually raise the barrel B to the position seen in Fig. 2. The entire device may then be moved over the floor in the desired direction, since the rollers 3 are preferably swiveled to the sections 1 and 2.

- When the barrel or other object being raised and transported, is conveyed to the proper place, the two sections 1 and 2 may 10 be again allowed to move to the position seen in Fig. 1 to lower the load, or the cable 12 may be released by unwinding the windlass 15, thereby lowering the weight to the 15 position seen in Fig. 3, without spreading the frame. The device may be used in the position seen in this last named figure, for hoisting and conveying in rather cramped quarters when it is impossible to spread the frame as above described.
- 20 From the foregoing description, taken in connection with the accompanying drawings it will be seen that a comparatively simple device has been provided for carrying out the objects of the invention, yet that the 25 efficiency thereof is not impaired by such simplicity.

Particular emphasis is laid upon the provision of the cables 18 and the windlass 21, since by this means the inverted V-shaped 30 frame may be gradually spread to lower its apex, or gradually contracted to raise the same.

One form of hoist has been described in connection with the device, but it will be 35 understood that other devices may be employed to equal advantage.

I claim:—

1. A device of the character described comprising an inverted V-shaped frame having its two arms hingedly connected at their 40 upper ends and provided with supporting members on their lower ends capable of being moved upon a support, a windlass on one arm of the frame, guides on both arms 45 thereof, and a flexible element passing over

said guides and wound around the windlass on one arm of the frame, the other end of said element being secured to the other arm of said frame.

2. A device of the character described 50 comprising a pair of inverted V-shaped frames, the two arms of each frame being hingedly connected at their upper ends, a transverse ridge bar extending from one hinge to the other hinge whereby to space 55 the two V-shaped frames, transverse bars spacing the lower ends of said frames, a bearing carried by one arm of each frame, the two bearings being alined, a windlass revolvably mounted in said bearings, guides 60 near the upper ends of the two arms of each frame, and flexible elements secured at one end to said windlass and at their other ends to the other arms of the frames, said elements passing over said guides, combined 65 with a grappling device suspended from the rigid bar.

3. A device of the character described comprising a pair of sections each having a pair of legs, hinge leaves secured to the 70 upper ends of said legs and having knuckles on their upper ends, the knuckles of one section interengaging those on the other section, a transverse ridge bar passing through the alined knuckles, a windlass rev- 75 olubly mounted on one of said sections, guides carried by both of the sections near the upper ends thereof, and a flexible element secured to said windlass and to the other section, said element passing over said 80 guides, combined with a grappling device suspended from the ridge bar.

In testimony whereof I have hereunto set my hand in presence of two subscribing witnesses.

CHARLES JOHN SCHERRER.
